UNITED STATES PATENT OFFICE.

LUCIEN W. HURFF, OF GALESBURG, ILLINOIS.

HANGER FOR EAR-CORN.

No. 919,173.

Specification of Letters Patent.

Patented April 20, 1909.

Application filed August 8, 1908. Serial No. 447,517

To all whom it may concern:

Be it known that I, LUCIEN W. HURFF, a citizen of the United States, residing at Galesburg, in the county of Knox and State 5 of Illinois, have invented certain new and useful Improvements in Hangers for Ear-Corn; and I do hereby declare that the following is a full, clear, and exact description of the invention, which will enable others 10 skilled in the art to which it appertains to make and use the same.

My invention relates to improvements in hangers for ear corn, and has for its object the provision of an all metal hanger adapted 15 to carry a large number of ears upon a relatively small hanger and to be placed thereon entirely separate from one another that they may dry out uniformly and in the most perfect manner preserve the vitality 20 of the corn; also, to adapt the hanger to be suspended in a corn crib so that the corn may be safe from vermin and also to provide a hanger that will meet all requirements at the smallest possible cost.

25 I am aware that what are known as corn trees and racks have been heretofore patented but none of them are made entirely of metal and all of them so far as I am aware, are unnecessarily cumbersome and complex.

30 That my invention may be more fully understood, reference is had to the accompanying drawings, in which—

Figure 1 is a side elevation of my device showing ears of corn attached. The length 35 of the device as I would employ it would be considerably longer than shown in the figure, however; Fig. 2 also shows a side elevation of a section of the device; Fig. 3 is a top plan view upon the line 3—3 of Fig. 2. 40 However, in this view, the central hanger wire is cut off; and Fig. 4 is a vertical section along one side of the hanger wire and particularly showing the manner of coiling the impaling prongs upon the main stem or hanger-wire. Fig. 5 is a detail view showing 45 a section of a hanger wire.

Referring to the drawings, A is a hanger wire adapted to be looped at the upper portion into the form of a ring or hook as it 50 may be desired, adapting it to be hung upon a proper support.

B are impaling prongs preferably made of steel wire adapted to be coiled upon the hanger wire, the respective folds of the coil meeting corresponding depressions in the 55 body of the hanger wire to adapt the said impaling prongs to be maintained in a fixed position so that they will neither slide up and down upon the hanger wire or be turned from right to left.

60 The impaling prongs are arranged in pairs, representing respective ends of the single wire that is coiled upon the hanger wire and are adapted to be sharpened at their ends to facilitate the penetration of the 65 pith of the ears of corn. A series of such pairs of impaling prongs are adapted to be arranged upon the hanger wire in as great number as may be desired and adapted to be arranged upon the hanger wire so that the 70 adjacent pairs of prongs will bear in a direction at right angles to each other. However, the adjacent pairs may be arranged at any angles so long as they are arranged so that the ears of corn may be placed thereon without 75 touching or interfering with each other. Preferably, I desire that the prongs shall bear upwardly at approximately the angle shown; however, they may be made to bear in any angle from the perpendicular hanger 80 wire without departing from the spirit of my invention.

In carrying out my invention, the simplest means that occurs to me of causing the coils of the respective pairs of impaling 85 wires to engage the perpendicular hanger wire is that the coils may be slipped down over the hanger wire and then by the stroke of a hammer upon the coil, its folds will be caused to be embedded within the body of 90 the hanger wire. However, depressions may be made in the body of the hanger wire and the coils then slipped down over the same and be caused to spring into such depressions and thereby be held in place.

95 What I claim is:

In a device of the class described, the combination of a hanger wire provided with a loop at its upper end adapting it to be hung in vertical position, a series of serrations disposed at intervals throughout the length of the wire hanger and disposed alternately in

different vertical planes, a series of pointed impaling prongs arranged in pairs, the respective pairs meeting in coils at the centers of the respective pairs, said coils flattened to 5 form an oblong central opening adapted to engage the different sets of serrations upon the vertical hanger, whereby the coils engaging the serrations will hold the impaling

prongs from vertical or circumferential movement upon the hanger wire. 10

In testimony whereof I have affixed my signature, in presence of two witnesses.

LUCIEN W. HURFF.
